COIL WINDING DEVICE

John A. Earl, La Grange, Ill., assignor to Western Electric Company, Incorporated, New York, N. Y., a corporation of New York

Application March 4, 1943, Serial No. 478,037

6 Claims. (Cl. 242—4)

This invention relates to coil winding devices and more particularly to devices for manually winding toroidal coils.

An object of the invention is to provide a simple and practicable device for efficiently and economically winding toroidal coils manually.

In accordance with the above object, the present invention, in one embodiment thereof, as applied to the winding of toroidal coils of a certain type used in the electrical arts, the dimensions of the coils being so minute that automatic winding machines cannot be employed practically, comprises a pair of plates each fixed to and extending perpendicularly from base members connected together by a hinge, the arrangement being such that the plates are maintained in predetermined relation when the base members are normally supported upon their lower faces. The upper ends of the plates are apertured and are counterbored in opposite directions to provide a circular recess for holding an annular core during the winding of a fine wire helically thereon to form a toroidal coil. A plurality of circularly arranged apertures are provided in the plates about the axis of the recess, the apertures in each plate being aligned with the apertures of the other plate when the plates are abutted. Formed in the plates and extending radially from each aperture and into the recess is a narrow slit. In using the device, a core is mounted in the recess and then an ordinary sewing needle having a fine wire threaded therethrough is passed through a set of the aligned circularly arranged apertures from one side of the device until approximately one-half of the length of wire is drawn through the apertures. Thereafter, the needle is passed through the core opening from the opposite side and then through the set of apertures next to the first set of apertures and continuing around the core in one direction to complete one-half the number of convolutions required, the wire being pulled through a slit each time, thus accurately guiding the wire and positioning, in spaced relation, the convolutions of wire on the core. The needle is then removed from the wire and the opposite end is threaded therethrough and the operations repeated for the other half of the core in similar manner.

Other objects and advantages of the invention will more fully appear from the following detailed description, taken in conjunction with the accompanying drawings, in which

Fig. 1 is an end view of a toroidal coil winding device embodying the features of the invention shown mounted on a bench fixture at a convenient angle for an operator who faces the left hand side thereof;

Fig. 2 is an enlarged fragmentary side view of the upper end of the device taken on the line 2—2 of Fig. 1;

Fig. 3 is a vertical section taken on the line 3—3 of Fig. 2, showing a toroidal core in position for winding and the manner of winding the wire convolutions thereon; and

Fig. 4 is an enlarged perspective view of a toroidal coil after completion and removal from the winding device.

Referring to the drawings in detail, 10 and 11 indicate base members hinged together, as indicated at 12, and channel-shaped at their lower faces to provide projecting foot-like supporting portions 13. Inner opposed vertical faces 14 of the base members 10 and 11 are slotted at 16 and fixed therein are perpendicularly extending plates 17, having their outer faces, which are shown abutting in Fig. 1, in the plane of the faces 14 of the base members. It will be apparent, with the base members 10 and 11 hinged in the manner shown, coincident with their inner faces 14, that when the device is resting upon the portions 13 or is mounted at an angle on a bench fixture, indicated in general at 18, inner faces 19 of the plates 17 will be maintained in abutting relation. To separate the plates 17, one or the other of the plates or base members is grasped and slightly elevated, whereupon the plates readily separate.

The plates 17, at their upper ends, which are reduced in thickness from the point 20 outwardly, as shown in Fig. 3, are each formed with a counterbored aperture 21, the apertures being oppositely directed and in alignment when the plates are abutted. With the plates 17 thus positioned, the larger diameters of the apertures 21 form a circular recess 24 open at both ends for freely peripherally receiving and supporting a toroidal core 25 placed in the aperture in one of the plates when the plates are separated, the core being prevented from moving axially from the recess when the plates are abutting by annular shouldered faces 26 at the junctures between the larger and smaller diameters of the apertures 21. Formed in each of the plates 17 in circular arrangement and spaced a suitable distance from and radially about the axis of the apertures 21 are a plurality of equally spaced apertures 27, which are tapered at their outer ends as indicated at 28. In the present embodiment, forty such apertures 27 are provided and the apertures in one plate 17 are in alignment with the apertures in the companion plate when the plates are abutted as shown in Fig. 3. Extending radially from each of the apertures 27 and into the recess 24 in each plate 17, is a narrow slit 31, the inner ends of the material between the slits being rounded or blunted, as shown at 32. To insure accurate alignment of the apertures 21, 27 and slits 31 of each plate 17 with those of the companion plate in case of play or looseness at the hinge 12 when the plates

17 are abutted, one of the plates carries a fixed pin 33 which enters an aperture 34 in the other plate and insures accurate alignment of the plates and thus the described apertures and slits.

In the use of the device, the plates 17 are separated in the manner previously described and a core 25 is placed in the aperture 21 of one of the plates 17. After abutting the plates 17, the core 25 will be contained in the recess 24 and upon either resting the device upon its foot-like portions 13 on a horizontal support, or, as shown in Fig. 1 in the bench fixture 18, in which it is arranged at a convenient angle for an operator, the plates 17 will be maintained in abutting relation to hold the core 25 therebetween. The operator then uses an ordinary sewing needle 35 (Figs. 1 and 3) with a fine wire 36 of suitable length threaded therethrough and passes the needle through one set of the aligned circularly arranged apertures 27 from the forward side of the device to the rear side thereof and then passes it through the center of the core to the forward side. The wire is drawn sufficiently taut to move it through the slit 31 communicating with the particular aperture 27 and into engagement with and around the core. The slit 31 serves to definitely guide the wire 36 and position the convolution thereof on the core 25 and spaces it from the adjacent convolutions of wire to be wound on the core. A preferred manner of winding the core 25 comprises drawing approximately one-half of the wire through the first set of apertures 27 and then continuing around the core in either direction to complete successive convolutions in the manner above described until one-half of the convolutions are completed. To retain the end of the wire 36 opposite the end threaded through the needle 35, it is wrapped around a pin 37 on the plate 17 at the forward side of the device. Thereafter, the needle 35 is removed from the wire 36 and a sufficient length of wire remains to provide a terminal or lead portion 38 (Fig. 4). The opposite end of the wire 36 is then detached from the pin 37 and threaded onto the needle 35 and the wiring of the other half of the core 25 is started in a direction opposite to the first winding operations by threading the wire 36 first through the center of the core 25 at the forward side of the device and then from the rear side of the device through the set of apertures 21 adjacent the first set of apertures used in winding the first half of the core, the operations continuing until the entire core is wound, whereupon the needle is removed from the wire and a sufficient length of wire remains to provide a terminal or lead portion 39 (Fig. 4). Before removing the wound coil from the device by separating the plates 17 in the manner previously described, a strand 40 of insulating material is threaded through the center of the coil and tied at a point between the two convolutions of wire which terminate with the lead portions 38 and 39 to insure complete separation thereof and thus prevent a drop in the potential of the coil. Also, before the removal of the wound coil from the device, a pin 41 of insulating material is passed through the center of the coil. The pin 41 serves as a means for mounting the coil in the mechanism on which the coil is used.

It will be understood that although, in the em-

bodiment of the device shown and described, the apertures 27 and slits 31 are equally spaced completely around the recess 24 for winding a particular form of coil, this arrangement may be varied for other types of coils. For instance, the convolutions of wire may be arranged in spaced groups and further that the slits 31 in certain arrangements of convolutions could be arranged parallel to each other instead of extending radially relative to the axis of the recess 24, as shown in the drawings. Also, it is not necessary that the plates be abutted in all cases, as is shown for the particular coil being wound.

It will be understood that the embodiment herein described is merely illustrative of the invention and one application thereof and that modifications can be made and it is capable of other applications.

What is claimed is:

- 20 1. A device for manually winding toroidal coils comprising means for supporting a core, said means being slotted at a plurality of points extending outwardly from and communicating with a core supported thereon to guide a strand to be annularly wound with the convolutions thereof in spaced relation upon the core.
- 30 2. A device for manually winding toroidal coils comprising recessed means for supporting a core therein, said means being slotted at a plurality of points extending outwardly from the recess and opening thereinto to guide a strand to be annularly wound with the convolutions thereof in spaced relation upon the core.
- 40 3. A device for manually winding toroidal coils comprising a pair of apertured members effective when predeterminedly associated with each other to support a core in the apertures thereof, said members being slotted at a plurality of points extending outwardly from the inner peripheries of the apertures to guide a strand to be annularly wound in spaced relation upon the core.
- 50 4. A device for manually winding toroidal coils comprising a pair of apertured members effective when predeterminedly associated with each other to support a core in the apertures thereof, said members having a plurality of radially directed slits extending outwardly from the inner peripheries of the apertures to guide a strand to be annularly wound with the convolutions thereof in spaced relation corresponding to the angular spacing of the slits upon the core.
- 60 5. A device for manually winding toroidal coils comprising a pair of apertured members effective when predeterminedly aligned, abutted, and maintained relative to each other to support a core in the apertures thereof, said members being slotted at a plurality of equally spaced points extending outwardly from the inner peripheries of the apertures to guide a strand to be annularly wound in equally spaced relation upon the core.
- 70 6. A device for manually winding toroidal coils comprising a pair of hinged members adapted to be abutted and having alignable counterbored oppositely directed apertures providing a recess for supporting a core therein, said members being slotted at a plurality of points extending outwardly from the recess and opening thereinto to guide a strand to be wound with the convolutions thereof in spaced relation upon the core.

JOHN A. EARL.
